UNITED STATES PATENT OFFICE.

JOHN A. F. SVENSON, OF PITTSBURGH, PENNSYLVANIA, ASSIGNOR TO THE STANDARD SCALE & SUPPLY COMPANY, OF PITTSBURGH, PENNSYLVANIA, A CORPORATION OF DELAWARE.

DISTRIBUTING MECHANISM FOR CONCRETE-MIXERS.

1,276,440.

Specification of Letters Patent. Patented Aug. 20, 1918.

Application filed February 16, 1918. Serial No. 217,697.

To all whom it may concern:

Be it known that I, JOHN A. F. SVENSON, a citizen of the United States, residing at Pittsburgh, in the county of Allegheny and 5 State of Pennsylvania, have invented certain new and useful Improvements in Distributing Mechanism for Concrete-Mixers, of which the following is a specification.

This invention relates to improvements in 10 distributing mechanism for concrete mixers, and has for its objects the provision of a mechanism of this class having a more universal and accurate range of adjustment than similar apparatus heretofore constructed, whereby to provide for distribution of 15 concrete at any desired point over an extensive range.

Other objects of the invention are to provide a novel construction of conveying receptacle and improved automatic control mechanism for the escape of material from 20 said receptacle, and to provide a generally improved structure of this class which may be conveniently manipulated and be generally efficient for the delivery of material 25 from a concrete mixer to any desired point on a street or other place where it is desired.

A further object is to so construct a distributing mechanism of this class that it may 30 be removed from a mixing machine to facilitate the movement thereof from place to place by removing a few bolts and uncoupling one shaft, therefore leaving the entire rigging intact and greatly facilitating the 35 operation of reassembling the device.

Generally stated, the mechanism comprises an adjustable boom adapted to extend beyond a mixer, a hopper or receptacle supported on and movable thereon and having 40 a drop bottom and automatic control mechanism for the drop bottom.

In the drawings:

Figure 1 is a side elevation of an apparatus embodying the invention;

45 Fig. 2 is an enlarged sectional detail view of a portion of the device showing the manner of adjustably supporting the boom, and the actuating mechanism for the bucket supporting trolley;

50 Fig. 3 is a horizontal sectional detail view on the line III, III of Fig. 2;

Fig. 4 is a fragmentary side elevation of the hopper or receptacle carriage, showing the release mechanism of the hopper bottom;

Fig. 5 is a view on the line V, V of Fig. 4; 55

Fig. 6 is a view at right angles to Fig. 4;

Fig. 7 is a vertical sectional view on the line VII, VII of Fig. 4;

Fig. 8 is a detail view in side elevation of the control mechanism for the hopper bottom; 60

Fig. 9 is a top plan view, partly in section, of the boom mounting and mechanism for imparting horizontal movement to the same;

Fig. 10 is a side elevation of the same on the line X, X of Fig. 9;

Fig. 11 is a vertical detail sectional view at the rear end portion of the boom on the line XI, XI of Fig. 2, showing the means 70 for mounting the guiding sheaves for the cables;

Fig. 12 is a plan view of the spring retracted sheave and its mounting at the end of the boom; and

Fig. 13 is a rear end view of the boom support showing a modified arrangement of adjusting cables.

Referring more particularly to the drawings, A designates a conventional form of 80 mixer having a truck 10 and mixing drum 11 adapted to discharge through spout 12 and to be rotated by a gear 13 meshing with gearing 14 on the drum. The gear 13 is loosely mounted on a constantly moving 85 shaft 15, and is engaged by a clutch 16 having operating lever 17 when it is desired to rotate the drum 12.

A supporting frame 18 is mounted on the truck and is provided at its forward end 90 with a bracket or support 19 adapted to support the boom 20.

A socket member or cup 21 is mounted on the frame 18 and bracket 19 and is adapted to receive and support the ball member 95 22 of the boom bearing. The upper frame of ball bearing member 22 is secured to the boom 20 by bolts 2 passing through the webs of the boom channels and the front portions of bearing 34 (Fig. 9). By reason 100 of the ball and socket support, boom 20 is allowed universal movement or adjust-

ment which permits unrestricted distribution of the mixed concrete, carried by the trolley and bucket, whether the ground be level or inclined.

5 The boom 20 is preferably of channel iron side members having their flanges turned inwardly to provide a track for the wheels of the traveling hopper carriage 24 supporting hopper 25.

10 The free end of boom 20 is adapted to be adjusted vertically by means of a suspension cable 26 secured by one end at 3 and passing around the anchor sheaves 28 mounted on supporting frame 29 secured on frame 15 18, and leading to a winding sheave 27. Cable 26 is adapted to be lengthened or shortened to lower or raise the boom 20 by being wound upon sheave 27 which is operated by means of hand wheel 30 connected 20 by suitable worm gearing to the shaft of sheave 27.

The frame of ball 22 is formed with a centrally arranged aperture or bearing adapted to receive a bearing and mounting sleeve 25 32 extending downwardly from and forming a part of a drum 33. The ball 22 has its side wall flared outwardly to form a bearing flange or partial drum 34, and has an upwardly projecting sleeve 31 which forms a 30 journal bearing for drum 33. A second drum 35 is removably secured to the lower end of the sleeve 32 by key 36' or any other suitable means.

The sleeve 32 of the drum 33 is adapted 35 to rotate freely within the journal-bearing aperture 31 in the ball 22 and is operated by means of shaft 36 having a universal connection 37 therewith to allow for continuous rotation regardless of the position of the 40 boom 20. The shaft 36 is detachably coupled to stub shaft 38 by coupling 39. Shaft 38 is supported in bracket 40 secured to frame 18 and has a beveled gear 41 on its upper end which is in mesh with gears 42 45 and 42' loosely mounted on shaft 43 which is mounted in suitable bearings 44 and 44'. Shaft 43 receives its power from the constantly rotating shaft 15 on the mixer through sprocket and chain connection 45. Gears 42 and 42' transmit power from the 50 shaft 43 to the shafts 38-36 by means of the friction clutches 46 and 47, respectively, which are connected by the lever rod 48 and operated by the lever 49. It will be readily 55 understood that one of the gears will cause the shaft 36-38, and consequently the drums 33 and 35, to rotate in one direction, while the other gear will act to move these parts in the reverse direction when their respective clutches have been moved into engaging position.

The hopper carriage 24 having wheels 51 is mounted to travel on the boom 20 and has downwardly projecting spaced side portions

52 and 53. Transverse carrying truss members 54 are secured to the bottom of the carriage and support the hopper 25 which comprises a four walled receptacle, the back and side walls of which are preferably vertical with the exception that they converge 70 inwardly near the bottom. The front wall is directed upwardly on an angle from the bottom to form a receiving spout. The bottom of the hopper is a cone-shaped member 55, operating like the bell and hopper of a 75 blast furnace, adapted to be releasably held in position by means of a rod 56 mounted within sleeve 57 which projects upwardly from the top of the cone bottom member. Rod 56 is provided with a cushioning spring 80 58 resiliently engaging the bottom 55.

Rod 56 is connected to a cable 59 trained over guide sheave 60 mounted in carriage 24 and over actuating sheave 61 to which it is secured.

85 Actuating sheave 61 is mounted on a spindle 62 (Fig. 7) in the frame of carriage 24 and has a projecting lug or tooth 63 thereon adapted to be engaged by the locking hook or dog 64 having a pivoted trigger projection 64' which is held in operative position by spring 65. Sheave 61 has a projecting lug 66 on its inner face adapted to be engaged by a co-acting clutch or lug 67 on the cable-actuated sheave 68 mounted on the 95 spindle 62.

The carriage 24 is adapted to be moved longitudinally of the boom 20 by means of a cable 69, secured to the lower drum 35, trained about guide sheave 70 and passing 100 one or more times around the sheave 68, then directed along the boom and over spring mounted sheave 71 at the forward end thereof, and back along the boom to guide sheave 72 and upper drum 33.

105 The sheave 71 is mounted on a spindle 71' journaled in journal blocks 71^a slidably mounted in slots 71^c in brackets 71^b. The spindle 71' also passes through side bars 71^e which pass through cross bar 71^f secured to the forward ends of the brackets 71^b and have coiled springs 71^g mounted therebeyond and bearing against said cross-head. Securing and adjusting nuts 71^h are mounted on the terminal ends of the side bars 71^e for 110 tightening or loosening the tension of such springs.

115 The mounting of the sheave 71 as above described permits a flexible action of such sheave and also allows for the taking up of 120 any slack in the cable 69 by means of the adjusting nuts 71^h and the tension of the coil springs 71^g.

125 For the purpose of equalizing the distribution of the cable on drums 33-35 each is provided with a spiral groove, one right and the other left hand, so that the cable will wind and unwind uniformly as to each

drum, *i. e.*, the upper and lower strands will approach toward and move from the horizontal center of the compound drum together. Guide sheaves 70 and 72 are rotatably mounted on elongated spindles *b* secured in frames *c* and the sheaves as thus mounted are free to rotate and rise or fall with the cable as it ascends or descends the grooved peripheries of the drums 33 and 35.

10 It will thus be seen that upon the rotation of the drums 33—35 in one direction the carriage will be pulled by one drum longitudinally of the boom, the cable being paid out by the other drum. On outward movement of the buggy, the sheave 68 is held against rotation by the lug 67 engaging the lug 66 on the sheave 61, which sheave is held against rotation by the hook 64.

15 The hopper bottom 55 is adapted to be released by suddenly reversing the movement of the cable 69 by winding it upon the drum 35. This will cause the sheave 68 to be revolved in an opposite direction so as to disengage the lug 67 from contact with lug 66 and cause the lug 67 to strike the trigger 64^a of catch 64, thereby releasing said catch from engagement with the stop or tooth 63 on the sheave 61. When sheave 61 has been released it will revolve due to the pull on the cable 59 of the load on bottom 55. The movement of the sheave 61 in lowering the bottom is limited by stop 73 which extends from the buggy frame into the path of and is engaged by the lug or tooth 63.

20 After the load has been discharged, the drums are again rotated to continue winding the cable upon drum 35 to bring the hopper back for a fresh load. This tends to revolve the sheave 68 but as the weight of the bottom 55 exerts a restraining tension on the cable, it ordinarily prevents the rotation of sheave 68 while its lug 67 engages lug 66 of the winding sheave 61.

25 The hopper bottom 55 remains in its lowered position until the hopper reaches its extreme rear loading position, indicated in dotted lines Fig. 1, at which point the hopper carriage will strike a bumper or stop 74. When the hopper carriage is thus arrested against the bumper 74, the continued winding of the cable 69 upon the drum 35 will revolve the sheave 68 causing the lug 67 to engage lug 66 on sheave 61 and thus rotate the sheave 61 back to its normal position, where it will be held by the engagement of the hook 64 on the lug 63. It will, of course, be understood that the cable 59 will be wound upon the sheave 61 when it is thus returned to its initial position and the bottom 55 will thereby be raised, as in Fig. 2.

30 The boom 20 is adjustable laterally to allow for a wide distribution of mixed concrete, by means of the hand wheel 75 which

is connected to threaded shaft 76 mounted 65 in bearings 77 on the frame 18 and having a movable block 78 thereon. A cable 79 is secured at its center to the block 78, trained about sheaves 78', and its ends are passed around an enlarged rounded exterior bearing face of bearing flange 34 in opposite directions and are secured thereto as indicated at 5. By this means the boom is swung around in one direction or the other, and any slack in the cable may be taken up 75 by the nut and bolt terminal connections shown.

35 In Fig. 13 I have shown a modified arrangement of the adjusting cables for moving the boom 20 laterally to provide for 80 equalization of the pull of the cables in either direction. Cables 79^a and 79^b are arranged in pairs as shown, and are secured in spaced relation at their center to the block 78 as already described. By this 85 means, the outermost cables pull equally and avoid any tilting tendency.

40 The operation of the device in detail is as follows: The parts being assembled in operative position with the hopper 25 at its 90 rearmost position, mixed concrete from the mixing drum 11 is discharged by the drum chute 12 into hopper 25; when the hopper is filled the lever 49 is operated to engage the proper clutch 46 or 47 with gear 42 or 42', 95 depending on the rotation of shaft 43, which will cause the cable 69 to be wound upon drum 33, thereby pulling the carriage 24 and hopper 25 outwardly on the boom 20. When the hopper has reached the desired 100 position, lever 49 is suddenly reversed, disengaging one clutch as 46 and momentarily engaging the other clutch 47 on gear 42', thereby causing a sudden reverse movement 105 of the cable. This will cause the sheaves 68 to be reversed and its lug 67 to strike the trigger 64^a of the hook 64, thereby releasing such hook and allowing the bottom-supporting sheave 61 to rotate until the lug 63 engages stop 73, thereby lowering the bottom 55 (Fig. 8).

45 Reengagement of the clutch 47 and its continued application will cause the carriage 24 and hopper 25 to move rearwardly on the boom 20 until the carriage strikes the stop 74 when the carriage will stop. Cable 69 will continue to move, however, revolving the sheave 68 in the opposite direction, which will then cause the sheave 61 to reverse, due to the engagement of the lug 67 against lug 66, thereby taking up the cable 59 and raising the bottom 55, and bringing lug 63 again under locking hook 64 (Fig. 4). Upon again reversing lever 49, drum 33 will wind on cable 69 tending to draw 120 the carriage outwardly of the beam, but sheave 68 will revolve inoperatively until lug 67 is swung around and comes into con-

tact with the opposite side of lug 66, as in Fig. 4. Thereupon, stop 63 being engaged by the shoulder 64, neither sheave can rotate and the cable will act to draw the carriage outwardly of the beam.

Trigger 64^a being spring-retracted will rise to allow passage of lug 67 and will resume its position for operation to unlock the sheave as already described.

10 Should any of the concrete stick around the bottom 55, it will not prevent sheave 61 from being rotated a sufficient distance to engage lug 63 under catch 64 since the cable 59 is secured to the rod 56 which has a 15 cushioning connection with the bottom 55 due to the spring 58.

It will be understood that the carriage 24 may be reversed to move rearwardly without necessarily discharging the material in 20 the hopper 25. This is accomplished by slowly and lightly engaging the clutch member 47 on gear 42'. The tension of the spring 65 is of such strength that unless the hook 64 receives a sudden and severe 25 stroke such hook will not be disengaged from the lug 63.

While I have shown a preferred embodiment of my invention, I do not wish to be limited to the exact construction shown, 30 since various changes in design and details of construction may be made by one skilled in the art without departing from the spirit of my invention as defined in the appended claims.

35 I claim:—

1. In combination with a socketed bearing, a distributing boom having a partly spherical member seated in said bearing, a carriage and hopper carried by the boom, means for 40 imparting movement to the carriage embodying winding drum mechanism journaled in said member, and means for swinging the boom laterally on said bearing.

2. In combination with a socketed bearing, a distributing boom having a partly spherical member seated in said bearing, a carriage and hopper carried by the boom, means for imparting movement to the carriage embodying winding drum mechanism 50 journaled in said member, and means for swinging the boom laterally and for raising and lowering it on said bearing.

3. In combination with a socketed bearing, a distributing boom having a partly spherical member seated in said bearing, a carriage and hopper carried by the boom, a pair of winding drums having a portion extending through said partly spherical member, a cable connected with the carriage 60 engaging a terminal sheave wheel and adapted to be wound and unwound by said drums, and means for rotating said drums in either direction.

4. In combination with a socketed bearing,

a distributing boom having a partly spherical member seated in said bearing, a carriage and hopper carried by the boom, a pair of winding drums having a portion extending through said partly spherical member, a cable connected with the carriage engaging 70 a terminal sheave wheel and adapted to be wound and unwound by said drums, a driving shaft having universal connection with said drums, and means for actuating said shaft in either direction. 75

5. In combination with a socketed bearing, a distributing boom having a terminal spring retracted sheave wheel and a partly spherical member seated in said bearing, a carriage and hopper carried by the boom, 80 a pair of winding drums having a portion extending through said partly spherical member, a cable connected with the carriage engaging said terminal sheave wheel and adapted to be wound and unwound by said 85 drums, a driving shaft having universal connection with said drums, and means for actuating said shaft in either direction.

6. In combination with a socketed bearing, a distributing boom having a partly 90 spherical member seated in said bearing, a carriage and hopper carried by the boom, a pair of winding drums having a portion extending through said partly spherical member, a cable connected with the carriage 95 engaging a terminal sheave wheel and adapted to be wound and unwound by said drums, a driving shaft having universal connection with said drums, and a shaft geared with said shaft and provided with reversible 100 clutch mechanism.

7. In combination with a socketed bearing, a distributing boom having a partly spherical member seated in said bearing, a carriage and hopper carried by the boom, 105 a pair of winding drums having oppositely disposed spiral grooves and a hollow cylindrical connecting portion extending through said partly spherical member, a carriage actuating cable having its terminals connected with said drums, slidably mounted 110 guide sheave for the cable, and a reversible power driven actuating shaft connected with said cylindrical connecting portion by a universal joint. 115

8. A universally adjustable distributing boom for a concrete mixer having a drop bottom hopper, a supporting carriage therefor, a raising and lowering sheave wheel thereon having a flexible connection with the hopper bottom, a co-acting sheave, a winding drum, and a cable connected therewith and wound upon said co-acting sheave whereby to provide for imparting movement to the carriage and also to the co-acting 120 sheave to raise or lower the hopper bottom. 125

9. A distributing boom for a concrete mixer having a longitudinally traveling car-

riage, a hopper depending therefrom provided with a closing bottom, a revoluble sheave on the carriage having a cable connected to the hopper bottom, a double winding drum, a relatively movable member on the carriage adapted to actuate the revoluble sheave, and a carriage propelling cable connected with the winding drum and operatively engaging said relatively movable member.

10. In combination with a concrete mixer having a supporting frame provided with a universal bearing support, an interfitting ball bearing member therein having a partly rounded outer portion and a fixedly attached distributing boom, a swinging cable passing in opposite directions around said outer portion and secured thereto and connected with adjusting mechanism, a carriage supported by said boom having a distributing hopper, a pair of winding drums having a portion rotatably mounted within the ball bearing member, means for actuating said drums in either direction, and a cable having its ends connected with said drums and engaging a portion of the carriage between its ends.

11. In combination with a concrete mixer having a supporting frame provided with a universal bearing support, an interfitting ball bearing member therein having a partly rounded outer portion and a fixedly attached distributing boom, a swinging cable passing in opposite directions around said outer portion and secured thereto and connected with adjusting mechanism, a carriage supported by said boom having a distributing hopper, a pair of winding drums having a portion rotatably mounted within the ball bearing member, means for actuating said drums in either direction, means for opening and closing the hopper supported on the carriage, and a cable having its ends connected with said drums and engaging said hopper opening and closing means between its ends.

12. A distributing mechanism for concrete mixers comprising a boom having universal movement with respect to the mixer, a carriage and hopper movable along said boom, means for moving said carriage, and mechanism embodying a sheave operated by the carriage moving means and a supporting sheave and cable controlled thereby for causing a discharge of material from said hopper.

13. A distributing mechanism for concrete mixers comprising a boom having universal movement with respect to the mixer, a carriage and hopper movable along said boom, a cable operable in reverse directions to impart corresponding movement to said carriage, and means embodying a sheave operated by said cable and a cable-supporting

sheave controlled thereby for causing a discharge of material from said hopper.

14. A distributing mechanism for concrete mixers comprising a boom having universal movement with respect to the mixer, a carriage movable along said boom provided with a hopper having a drop bottom, a cable operable in reverse directions to impart movement to said carriage; and means embodying a sheave operated by said cable and a cable-supporting sheave controlled thereby for lowering the hopper bottom to discharge the contents thereof.

15. A distributing mechanism for concrete mixers comprising a boom having universal movement with respect to the mixer, a carriage movable along said boom provided with a hopper having a drop bottom; a cable operable in reverse directions to impart movement to said carriage, and means operated by said cable for lowering the hopper bottom to discharge the contents thereof and for raising the hopper bottom to closed position, consisting of a bottom supporting cable and sheave and a co-acting sheave engaged by the carriage moving cable.

16. In a distributing apparatus for concrete mixers, the combination with a boom having universal movement with respect to the mixer, drums on said boom, and a cable trained along said boom and connected to said drums, of a carriage and dumping bucket mounted on said boom and movable longitudinally thereof, said carriage being connected with and adapted to be moved by said cable, said bucket having a drop bottom, and a pair of sheaves on said carriage for releasably supporting said bottom, one of said sheaves being operated by the reverse movement of said cable.

17. In a distributing apparatus for mixing machines, a boom, a carriage movable along said boom provided with a hopper having a drop bottom, a drum actuated cable operable along said boom to impart movement to said carriage, and means adapted to be operated by said cable for releasably supporting said bottom, comprising a sheave wheel journaled in said carriage and having a flexible supporting member secured thereto and to said drop bottom, a second sheave wheel journaled within said carriage and operatively engaging said cable, co-acting lugs on each of said sheaves arranged to travel in the same annular path, and a locking dog engaging said first named sheave adapted to normally hold it against rotation, said dog being adapted to be released by the engagement therewith of the lug on said second named sheave when said cable is reversed.

18. The combination with a mixing machine comprising a base, a mixing drum, a continuously rotating shaft on said base and

- adapted to be geared to said drum, and a supporting frame on said mixer having a projecting bracket on its forward end, of a boom having a rocking connection with said bracket, a pair of drums journaled on the rear end of said boom, a shaft for operating said drums, a stub shaft mounted in said frame and connected with said first named shaft, clutch and gear connection between 10 said second named shaft and said stub shaft, a cable trained along said boom and secured to said drums, a carriage movable along said boom, a hopper secured on said carriage having a drop bottom, a pair of sheave wheels secured on a shaft carried by said carriage, a flexible supporting member secured to said drop bottom and to one of said sheaves, each of said sheaves having a lug adapted to travel in the same annular 15 path, a locking dog adapted to engage a projection on the sheave having the supporting member thereon to hold it against rotation, the other of said sheaves being adapted to be rotated by the forward movement of said 20 cable until said lugs engage each other and to rotate in the reverse direction when said cable is reversed, whereby to release the locking dog to permit the drop bottom to fall.
19. The combination with a mixing machine having a supporting frame, and a projecting bracket thereon, of a boom having universal movement with respect to said machine, a pair of drums journaled on said boom, a shaft having a universal connection 30 with said drums, a clutch and gear connection for said shaft adapted to connect it with a source of power, a cable trained along said boom and secured to said drums, a carriage movable along said boom, a hopper secured on said carriage having a drop bottom, a pair of sheave wheels secured to a shaft journaled within said carriage, means secured to one of said sheaves supporting the drop bottom, the other of said sheaves 40 being operatively connected with said cable, means for locking said sheaves against rotation when said carriage is moved in a forward direction, and means for releasing said sheaves to permit a limited reverse movement when said cable is reversed thus permitting said bottom to drop.
20. The combination with a mixing machine having a supporting frame, and a projecting bracket thereon, of a boom having a ball and socket connection with said bracket to allow for universal movement, means for moving said boom on a horizontal plane, other means for moving said boom vertically, a pair of drums journaled on said 50 boom, a shaft having a universal connection with said drums, a clutch and gear connection for said shaft adapted to connect it with a source of power, a cable trained along said boom and secured to said
- drums, a carriage movable along said boom, a hopper secured on said carriage having a drop bottom, a pair of sheave wheels secured to a shaft journaled within said carriage, means secured to one of said sheaves supporting the drop bottom, the other of said sheaves being operatively connected with said cable, means for locking said sheaves against rotation when the carriage is moved in a forward direction, and means for releasing said sheaves to permit a limited reverse movement when said cable is reversed thus permitting said bottom to drop. 70
21. The combination with a mixing machine having a supporting framework, and a bracket on the forward end thereof; of a distributing mechanism comprising a boom having a ball and socket connection with said bracket, means for moving said boom on a vertical plane, means for moving said boom horizontally, a carriage movable longitudinally of said boom, a hopper supported on said carriage and having a drop bottom, a cable operable longitudinally of said boom and adapted to move said carriage, and a sheave on said carriage adapted to releasably support a cable connected with the drop bottom of the hopper, and a controlling sheave therefor adapted to be operated by said carriage moving cable. 75
22. The combination with a mixing machine having a supporting frame arranged thereon, and a bracket supported on the forward end of said frame; of a distributing apparatus comprising a boom mounted on said bracket and having universal movement with respect to said mixer, a carriage and hopper movable along said boom, said hopper having a drop bottom, a cable operable along said boom to impart movement to said carriage, and means adapted to be operated by said cable for releasably supporting said bottom, said means comprising a sheave wheel journaled in said carriage and having a flexible supporting member secured thereto and to said drop bottom, a second sheave wheel journaled within said carriage and operatively engaging said cable, lugs on each of said sheave wheels arranged to travel in the same annular path, and a locking dog engaging said first named sheave wheel adapted to normally hold it against rotation, said dog being adapted to be released by the engagement therewith of the lug on said second named sheave wheel when said cable is reversed. 90
23. The combination with a mixing machine having a supporting frame thereon; of a distributing apparatus supported on said frame and having universal movement with respect thereto, a pair of drums mounted on said boom, a cable secured to one of said drums and trained along said boom and back over the same and adapted to be 100
- 110
- 115
- 120
- 125

wound upon the other of said drums, a carriage movable along said boom and connected with said cable, a hopper supported on said carriage and having a drop bottom 5 adapted to be supported by a flexible member passing over a sheave journaled in said carriage, a second sheave journaled within said carriage adapted to be moved by said

cable, means for normally holding said sheaves against rotation, and means for releasing said sheaves when said cable is operated in the reverse direction to allow said drop bottom to operate. 10

In testimony whereof I hereunto affix my signature.

JOHN A. F. SVENSON.
